MEANS FOR FORMING THREADED WIRE

Charles D. Toney, Jr., Atlanta, Ga., assignor to The Auto-Soler Company, a corporation of Georgia
Original application Feb. 14, 1962, Ser. No. 173,197.
Divided and this application July 21, 1965, Ser. No. 482,974

5 Claims. (Cl. 72—103)

This is a division of application Serial No. 173,197, filed February 14, 1962, now abandoned, and is related to co-pending application Serial No. 430,034, filed February 2, 1965, which latter application claims the product and process of the present invention and is a continuation of the aforesaid application Serial No. 173,197.

The present invention relates generally to threaded wire and particularly to a new and unique method and means for forming threaded wire in an expeditious and inexpensive manner.

The threaded wire produced by the present invention lends itself to advantage particularly for use with fastener forming and inserting machines in which wire is formed into fastener lengths and inserted into objects to hold them together; the threaded surface configuration enhancing straight driving and holding strength characteristics of the fasteners formed and inserted by these machines. A representative example of such a fastener forming and inserting machine is illustrated and described in U.S. Patent No. 2,944,758, issued July 12, 1960.

Briefly described the threaded wire of the present invention is produced by impressing discontinuous segments of spiral, thread-like grooves at the surface of a wire to be threaded, while causing the impressions to progress in a spaced sidewise succession about the wire in a spiral path. Preferably the impressions are made in a pair of diametrically opposed spiral paths with the pitch of the paths such that the paths complement each other in a generally contiguous alternation along the length of the wire, which contiguity in combination with a general spiral alignment of the groove segments of adjacent paths produces substantially continuous thread-like spiral grooves around the wire.

Such impression of discontinuous groove segments at the surface of a wire in a sidewise succession following a spiral path is obtained according to the present invention with means characterized by a cylindrical die having a die surface formed at a circumferential concavity with configuration forming segments extending across said concavity, which is shaped in relation to the configuration forming segments such as to dispose the segments in a discontinuous segmental forming array. This concave die surface provides extended contact with the surface of a wire when the wire is seated diagonally in the concavity. Also, the diagonal positioning of the wire with respect to the concavity results in the die surface following a spiral path when it is rolled around the wire to impress the die configuration thereat. A pair of such dies arranged in diametrical opposition and at a proper inclination will impress groove segments in the aforementioned pair of complementary contiguous spiral paths with the segments of adjacent paths being contiguous and cumulative.

To impress thread-like groove segments on the wire with these dies, their die surfaces are formed with spaced, parallel ridges that extend across the concavity at an inclination thereto less than the inclination of the diagonally seated wire so that the groove segments formed by the ridges of the dies will extend across the discontinuous spiral paths of impression on the wire, thereby permitting arrangement of the grooves of adjacent paths in alignment to form substantially continuous thread-like grooves.

The above described concave die surface feature of the die of the present invention is particularly applicable to

2

the production of the threaded wire of the present invention using the method of the present invention. However, this concave die surface feature is applicable as well to the production of surface configurations other than threads or grooves.

Although the term "threaded" is used throughout the present specification and claims it should be understood that this term is not intended to be limited to a strict interpretation as the "thread" of the present invention may be merely a simulated thread and need not have a truly helical configuration nor be truly continuous.

The features and advantages of the present invention will be apparent from the following description and accompanying drawings, in which:

FIG. 1 is a diagrammatic illustration of an apparatus for carrying out the principles of the present invention with a pair of forming dies of the present invention;

FIG. 2 is a plan view of a forming die of the type illustrated in FIG. 1 with an indication of the preferred diagonal position of a wire for proper die forming engagement of the wire by the die; and

FIG. 3 is a plan view of a length of threaded wire according to the present invention and illustrating the position of the forming dies for forming the threaded configuration in accordance with the present invention.

The present invention will now be described in relation to a preferred embodiment in which a surface forming die is used in a method of spirally configuring wire to produce a threaded wire. This threaded wire 10 has threads 12 formed by spaced spiral grooves 14 with flat spiral surfaces 16 therebetween. This threaded configuration provides particularly desirable improved straight driving and holding strength characteristics in fasteners formed from this wire.

The threaded wire 10, illustrated in substantial enlargement in FIG. 3, is produced according to a preferred embodiment of the present invention using the forming apparatus 20 illustrated in FIG. 1. This apparatus 20 includes thread forming means 22 that impress a surface configuration on the wire 10 as it is drawn through the apparatus 20.

The thread forming means 22 comprises a pair of die rolls 30 disposed in diametrical opposition with respect to the traveling wire 10. These rolls 30 are each mounted for free rotation in a yoke 24 slidably supported in a rotating assembly indicated diagrammatically at 28, and urged diametrically inwardly by suitable biasing means indicated diagrammatically at 26, which may be in the form of a spring or a lever arm actuated by centrifugal force or any other suitable means. The yokes 24, rotating assembly 28 and biasing means 26 constitute means for mounting the die rolls 30 in operating relation.

The details of the assembly construction 28 do not form a part of the present invention and can be of any suitable conventional construction. This assembly 28 is mounted for rotation in the direction of the arcuate arrow in FIG. 1 and suitable drive means (not shown) are provided to impart positive rotation to the assembly 28, thereby revolving the die rolls 30 around the wire 10 as the wire is drawn through the forming apparatus 20 with the diametrical opposition of the rolls 30 and the urging of the biasing means 26 causing the wire 10 to be tightly clamped between the rolls 30 for impressing the surface configuration of the rolls onto the surface of the wire. In addition, the yokes 24 are inclined to position the rolls 30 with their axes inclined to a plane perpendicular to the axis of the wire and with the rolls equally inclined but in opposite directions so that as the wire is drawn through the forming apparatus 20 with the assembly 28 rotating the die rolls 30 will progress around the surface of the wire 10 in spiral paths.

One of the die rolls 30 is shown in FIG. 2 substantially enlarged for clarity of detail. This roll 30 is seen to com-

prise a cylindrical body 32 around the circumference of which there is formed an arcuate concavity 34 having a die surface 36 of a desired configuration to produce by impression the desired configuration at the surface of the wire. To produce the previously described threaded surface 12 on the wire 10 the die surface 36 of the circumferential arcuate concavity 34 is composed of spaced substantially parallel ridges 38 with complementary grooves 40 therebetween. These ridges 38 and associated grooves 40 extend across the arcuate concavity 34 at an inclination with respect to the axis of the die roll 30 with the result that the ridges 38 impress discontinuous groove segments 42 at the surface of the wire 10 that extend across the paths of impression.

The circumferential arcuate concavity 34 is formed with a radius of curvature greater than the radius of the wire to be formed so that when the roll 30 is inclined with respect to the wire as aforementioned during the forming operation, the wire 10 will be seated in the concavity with extended contact between the die surface 36 of the concavity 34 and the surface of the wire 10. The concavities 34 are shaped in relation to the ridges 38 such as to dispose the ridges of each die roll 30 in a discontinuous segmental forming array substantially fully across the concavity. In the preferred embodiment the concavities 34 of the die rolls 30 are shaped in relation to the wire size and respective inclination to provide forming contact substantially fully across the width of the concavities 34, thereby forming discontinuous groove segments 42 at the surface of the wire 10 in paths 44 and 46 (FIG. 3) of widths substantially equivalent to the width of the concavity 34.

As the die roll 30 follows a spiral path 44 around the wire 10 the ridges 38 make spiral contact with the wire surface and therefore form the groove segments 42 in a spiral configuration. In order to form the groove segments 42 so that they extend across the paths 44 and 46 in the same spiral direction as the paths but at a greater pitch (the advance measured longitudinally along the wire of one complete spiral revolution) than the path, the ridges 38 of the die surface concavity 34 are inclined to the circumferential center line of the concavity at an angle less than the corresponding inclination of the inclined or diagonal position of the wire 10.

With a pair of rolls 30 operating in the forming apparatus 20 of FIG. 1, the wire is formed with two diametrically opposed paths 44, 46 (FIG. 3) with the angle of inclination of the rolls and the width of the path-forming concavity being related to form the paths 44 and 46 in substantial contiguity with the individual revolutions of the paths being disposed in adjacent contiguous alternation along the length of the wire 10. The location of the contiguous edges of the paths 44 and 46 is indicated by the dash lines 48 in FIG. 3. The location of the rolls with respect to the wire to form these paths is seen in dot-dash lines in FIG. 3 with the front roll indicated as 30a and the back roll indicated as 30b.

In the preferred embodiment, the grooved segments 42 of adjacent paths 44, 46 are generally spirally aligned in cumulative relation to produce substantially continuous thread-like grooves across the paths along the entire length of the wire 10. This alignment is accomplished by forming the die rolls 30 with identical die surfaces 36 so that the ridges 38 have the same pitch on each die. As these dies progress around the surface of the wire the ridges 38 on each die tend to align themselves with the adjacent groove segments 42 in the contiguous path formed by the opposite die. To continue this general spiral alignment throughout the length of the wire, the groove segments 42 in succeeding revolutions of the same path should be spaced with relation to the lengths of the spiral path revolutions so that there is general spiral alignment of grooves in succeeding revolutions of each path as well as alignment of grooves in adjacent revolutions of the different paths.

However, it is not necessary that precise alignment be obtained in adjacent revolutions of the different paths and in succeeding revolutions of the same paths. Thus the alignment shown in FIG. 3 may vary, due, for example, to slight misalignment or slight skew of the curvature imparted at the ends of the ridges 38. A general spiral alignment is all that is desired in the threaded configuration for most purposes.

The depth and width of the grooves 14 and therefore the width of the flat surfaces 16 are dependent upon the degree of impression of the ridges 38 of the die surfaces 36 of the rolls 30. If the force of the biasing means 26 is increased, the degree of impression of the ridges 38 will thereby increase the depth and width of the formed grooves 14 and decrease the width of the intermediate flat surfaces 16.

In the embodiment illustrated, the spiral thread-like grooves are produced with the dies 30 inclined at an angle of 35 degrees with respect to the length of the diagonally seated wire, with the diametrically opposed rolls being oppositely inclined at the same angle to produce spiral paths inclined at this same 35° angle. The ridges 38 on the die surfaces 36 of the rolls 30 are formed at an inclination of 25° to the circumferential center of the die, thereby producing a 10° inclination of the ridges with respect to the wire, which ridges impress grooves 40 on the wire 10 at this same 10° angle.

The present invention has been described in detail above for purposes of illustration only and is not intended to be limited by this description or otherwise except as defined in the appended claims.

I claim:

1. A surface forming die comprising a cylindrical body having a die surface formed at a circumferential arcuate concavity of a radius of curvature greater than the radius of a cylindrical object to be formed and having configuration forming segments extending across said concavity, said concavity being shaped in relation to said configuration forming segments such as to dispose said segments in a discontinuous segmental forming array substantially fully across said concavity, said body being adapted for rolling diagonally around the length of material to impress the discontinuous configuration segments in a spiral path.

2. A die for impressing a spiral configuration on a length of wire comprising a cylindrical body having a circumferential arcuate concavity of a radius of curvature greater than the radius of the length of wire and with a die surface thereat formed by spaced ridges extending across the concavity, said concavity being shaped in relation to said spaced ridges such as to dispose said ridges in a discontinuous segmental forming array substantially fully across said concavity when the wire is seated diagonally in the concavity, said body being adapted for rolling diagonally around the wire to impress said ridges into forming engagement with the surface of the wire and thereby form thereat a plurality of discontinuous segments of grooves in spaced sidewise succession in a spiral path.

3. Means for impressing a desired surface configuration on a length of wire comprising at least two dies, each of said dies having a cylindrical body and a die surface formed at a circumferential arcuate concavity of a radius of curvature greater than the radius of the length of wire with configuration forming segments extending across said concavity, said concavity being shaped in relation to said configuration forming segments such as to dispose said segments in a discontinuous segmental forming array substantially fully across said concavity, means for mounting said dies for rolling in equally spaced circumferential relation around the length of wire with the dies inclined with respect to the wire to cause the rolling of said dies to progress about the wire in adjacent spiral paths and to provide seating of the wire diagonally in the die concavities for extended contact of the wire across the concavities such that each die impresses discontinuous configuration segments on the wire with the discontinuous segments of adjacent paths being cumulative.

4. Means for impressing a desired surface configuration on a length of wire comprising a pair of dies having cylindrical bodies with die surfaces formed at circumferential arcuate concavities with configuration forming segments extending across said concavities, the radius of curvature of each of said concavities being greater than the radius of the length of wire, said concavities being shaped in relation to said configuration forming segments such as to dispose said segments in each concavity in a discontinuous segmental forming array, means for mounting said dies for rolling in diametrically opposed relation around the length of wire with the dies inclined with respect to the wire to seat the wire diagonally in the concavities such that said dies impress discontinuous configuration segments on the wire in adjacent contiguous spiral paths with the discontinuous segments of adjacent paths being contiguous and cumulative.

5. Means for impressing a desired surface configura-

tion on a length of wire according to claim 4 and characterized further in that said configuration forming segments are in the form of spaced ridges extending said concavities at a lesser inclination to the circumferential direction of the concavities than the inclination of the diagonally seated wire and proportioned to impress discontinuous groove segments at the surface of the wire with the discontinuous groove segments in one path in generally spiral alignment with the discontinuous groove segments in the other path.
